UNITED STATES PATENT OFFICE.

EDWARD B. HESS, OF NEW YORK, N. Y., ASSIGNOR TO ROYAL TYPEWRITER COMPANY, OF HOBOKEN, NEW JERSEY, A CORPORATION OF NEW JERSEY.

WRITING-MACHINE.

No. 874,892.

Specification of Letters Patent.

Patented Dec. 24, 1907.

Application filed February 3, 1905. Serial No. 244,022.

To all whom it may concern:

Be it known that I, EDWARD B. HESS, a citizen of the United States, residing in the borough of Brooklyn, city and State of New York, have invented certain new and useful Improvements in Writing-Machines, of which the following is a specification.

This invention comprises tabulator devices of novel construction and operation; and the combination of tabulator devices with line-lock devices so arranged that each time the carriage is arrested, when jumped for printing in a new column, the type bars will be prevented from moving to the printing point until after the carriage-arresting stops are disengaged. The line-lock devices employed in this new combination, are preferably of the class in which a barrier or interceptor is moved into the path of some part of the several type-bars to prevent any type-bar from traveling to the printing-point should its key be depressed.

In the accompanying drawings which show this invention in a form that experience has shown to be practical and efficient, and which illustrate so much only of a writing machine as is required for an understanding of the construction and mode of operation of the invention, Figure 1 is an elevation, with some parts broken away, viewed from just in front of the escapement; Fig. 2, a longitudinal vertical section looking from the left of the machine; Fig. 3, a similar view from the right; Fig. 4, a detail plan view, with the margin stop rail omitted; Fig. 5, a detail perspective view of the rack disengaging lever; Fig. 6, a diagrammatic detail plan showing the relation of the tabulator stops; Fig. 7, a detail elevation showing the margin stop and its rail; and Fig. 8, a plan view thereof.

The platen 1 is appropriately mounted in the carriage end plates 2, shown as connected by front and rear cross bars 3, 4, the latter of which bears upon a roller 5 mounted in a bracket 5' on the frame. At the front the carriage runs on balls 6. The type-bars 7 suitably pivoted in a segment 8 below the platen extend toward the front of the machine, normally resting upon the segmental back stop or rest 9. In the keyboard frame 10, above the type-ends or heads of the type-bars, is pivotally hung a type-bar locking segment 11, co-extensive with the curved or segmental assemblage of type-bar heads, and normally swung toward the front of the ma-

chine out of the paths of travel of the type bars in their excursions to the printing point.

At one side the locking segment 11 is connected by a link 12 with one arm of a bell-crank lever 13 pivoted at the rear of the machine, and having its other arm connected by link 14 with the movable member 15 of a two-part frame-stop of the tabulator and margin stop devices. This stop is located in rear of the platen and preferably in, or about in, the center of the machine. The part 15 is disposed vertically and pivoted, on an axis 15', at right angles to the platen, upon the similarly disposed member 16 pivoted on an axis 16' parallel with the platen, in a bracket 17 secured to the rear plate 18 of the frame. It will thus be seen that the two-part frame stop comprises a frame member pivotally mounted upon an axis extending laterally of the machine frame or parallel to the stop bar and adapted to be swung transversely to the stop bar, and a stop member proper mounted on the frame member on an axis perpendicular to the stop bar so as to be swung laterally of the machine frame or in a plane parallel to the stop bar, this stop being spring held or cushioned and adapted to be engaged by a carriage stop. The movement of the stop frame transversely to the stop bar permits the stop to be thrown in line with the carriage stops, while the lateral movement of the spring cushioned stop when engaged by the carriage stops operates to move the line lock devices and also acts as a buffer for the carriage. The upper end of 16, is shown rectangular in plan, while 15 is thin or flat and has a limited movement to and from the side of part 16. A coiled spring 19 having one end connected to the frame and the other to bell-crank 13 normally holds the part 15 away from 16 and by the thrust upon link 12 holds the locking segment 11 out of the paths of the type-bars.

The lower end 16' of upright member 16 extends as at 16' toward the right-hand side of the machine, and has its forwardly bent end slotted to receive a link (not shown) operated by a key in the board, to, at will rock the part 16 longitudinally of the machine to disengage stop 15 from the margin stop. This arrangement forms part of margin-stop devices shown and specifically claimed in my application No. 243,439 filed January 30, 1905.

The parts 15, 16, may rock longitudinally of the machine and are normally retracted or thrown toward the front of the machine by a spring 19.

- 5 In rear of the parts 15, 16, is a tabulator bar 20, having recesses in its front face. Adjustably seated on it are tabulator stops 21, which are made as thin as is consistent with required strength and stability. They are 70
10 each formed with a front leg 21' that fits in the recesses in the bar, and with oppositely extending lugs 21² that bear upon the rear face of the bar. This makes the stops readily movable for adjustment and gives them 75
15 stability in position on the bar.

Back of the lower end 16' of the part 16 is a cam plate or wiper 22 carried by a rock-shaft 23 having at the side of the machine a radial arm 24 from which a link 25 extends 80
20 to the stem 26 of a tabulator key or finger piece 27. A spring 28 applied to the rock-shaft holds the wiper 22 retracted. Extending down alongside of the lever 16 is the lower end of an angular rack-bar release 85
25 lever 29 pivoted at 30 in the frame bracket 5' and from thence extending forward. Its front end has a flat lateral horizontal extension 31 to the upper face of which is attached a piece of leather or other friction producing 90
30 material 32, above which is a rearwardly extending horizontal plate or flange 33 attached to or forming part of the carriage feed-rack 34 normally engaging the pinion 35 on the shaft of the escapement wheel 36.
35 Attached to the ends of the rack are rearwardly extending arms 37 pivoted at 38 in the side plates 2 of the carriage and having applied to one (or each of them) a spring 39 that acts to normally hold the rack in engagement with the pinion.
40

When the tabulator key 27 is depressed the wiper 22 is rocked forward carrying with it the feed rack-bar release lever and the lever 16 and with the latter the laterally movable lever 15. The extent of movement is sufficient to carry the member 15 into position to engage the tabulator stop-plates 21, and is permitted by the slot 16^a in the forwardly bent end of the part 16². When the 100
50 printing in one column is finished, the tabulator key is depressed and the feed-rack being moved out of engagement with its pinion, the carriage moves forward subject to the braking action of the surface 32 on the under face of the feed rack flange 33, until the part 15 strikes the next tabulator stop-plate 21, when the carriage will be arrested and the type-bar locking segment swung forward to lock the type-bars, so that if at that moment a printing key were depressed printing could not occur. On release of the tabulator key the parts all return to normal position and printing in the next column may be proceeded with.
65

The stop member 15 is made thin and ex-

tends rearwardly beyond the part 16; and the rearward movement of the two is sufficient to bring the former, but not the latter, into engagement with the tabulator stops, which are also quite thin, and the construction is designed to be such as to have as little lost motion as practicable in the passage of the frame stop 15, 16, from normal position to that in which it will engage the tabulator stops. The shift to a new column may be 75 made within two letter spaces, making printing in very narrow columns entirely feasible. The organization or adjustment is such that the carriage feed rack is first thrown out of engagement with its pinion and then a very slight rearward movement of the part 15 brings it into position to engage the tabulator stop next in position to arrest the carriage and throw the type bar locking segment across the paths of the type bars. The 85 spring cushioned part 15 also acts as a cushion to diminish its shock of impact against the tabulator stops, and its movement is limited by part 16 which acts as a positive stop for it.
90

Extending between the side plates and in front of the parts 15, 16, is a margin stop bar 40 having recesses in its upper face to receive the spring locking latch 41 of adjustable margin stop 42, that has a projection 43, extending rearward sufficiently to strike the laterally movable spring supported part 15 when the latter is in normal position. When 15 strikes stop 43 the shock is spring cushioned and the carriage arrested. As described in my application before mentioned the part 16, and with it 15, may be moved rearwardly, to disengage 15 from 43 to permit printing of one or more characters at the end of the line, by drawing 16² forward. Such 100
105 forward movement of 16² and rearward movement of 15 is however, preferably not sufficient to bring the latter into the plane of the tabulator stops, nor to disengage the rack. This organization, therefore, has a 110 part, as 15 movable perpendicular to the axis of the platen and adapted to co-operate in one position with a margin stop device and in another with tabulator stops. While the 115 general arrangement or relation of these parts as shown is believed to be new, the parts may be otherwise disposed or related.
125

The stop 15—16 has the dual function of engaging, when in normal position, a margin stop; of being moved out of engagement with the margin stop to permit printing of one or more letters at the end of a line; and of being moved into and out of engagement with a plurality of tabulator stops for multiple column printing.
130

No claim is made herein to the line lock devices *per se* as they form the subject-matter of another application filed by me January 30, 1905, Ser. No. 243,440. The combination of the line lock and margin stop de-

vices is claimed in my application Ser. No. 243,439 hereinbefore mentioned.

I claim as my invention:

1. In a writing machine, coöperating tabulator stops adapted to arrest the carriage in a plurality of positions for multiple column printing, combined with line lock devices and an operating connection therefor actuated by engagement of the tabulator stops to actuate 10 the line-lock devices to prevent printing, and by disengagement of the stops to restore the line-lock devices to normal position.

2. In a writing machine, tabulator devices comprising a rail adapted to carry a plurality 15 of tabulator stops arranged for multiple column printing, a stop adapted to coöperate with the respective tabulator stops and means for jumping the carriage from one tabulator stop to another, combined with line-lock devices and an operative connection between 20 the latter and the tabulator devices whereby the line-lock devices are put into operation whenever the carriage is arrested by the coöperating stops.

3. In a writing machine, tabulator devices comprising a rail adapted to carry a plurality of tabulator stops arranged for multiple column printing, a stop adapted to coöperate with the respective tabulator stops and means 30 for jumping the carriage from one tabulator stop to another, combined with a type-bar interceptor adapted to be interposed in the paths of and to lock the type bars and an operative connection between it and the tabulator devices whereby the type bars are locked whenever the carriage is arrested by the coöperating stops.

4. In a writing machine, tabulator devices comprising a tabulator stop rail, stops adjustably mounted thereon, a movable stop, carried by the frame, composed of two members one mounted upon the other and movable relative thereto and spring held away therefrom, a tabulator key in the key board 45 and an operative connection between it and the two part movable tabulator stop on the frame whereby the latter on the depression of the key may be moved into such position that the spring held member thereof will engage the tabulator stops on the bar to arrest the carriage, in combination with means for locking the type bars and an operative connection between said means and the spring held member of the frame tabulator stop 50 whereby when the carriage is arrested the type bars are locked and are unlocked when the tabulator stops are disengaged.

5. In a writing machine, the combination of a tabulator bar mounted in the carriage 60 parallel with the axis of the platen, adjustable tabulator stops thereon, a spring cushioned tabulator stop movable transversely to the tabulator bar and mounted in the frame, means for moving the rack of the machine 65 out of engagement with the escapement pin-

ion, a tabulator key, an operative connection between it and the spring cushioned tabulator stop and the means for disengaging the rack whereby on actuation of the key the rack is disengaged and the spring cushioned tabulator stop is moved into position to engage the adjustable tabulator stops on the carriage, means for locking the type bars and an operative connection between the latter and the spring cushioned tabulator stop, for the purpose set forth.

6. In a writing machine, the combination of a tabulator bar carried by the carriage, tabulator stops adjustably mounted thereon, a tabulator stop mounted in the frame and 70 movable transversely and longitudinally to the tabulator rail, means for disengaging the rack, a tabulator key and operative connection between it and the tabulator stop on the frame and the means for disengaging the 75 rack, means for locking the type bars and an operative connection between the latter and the movable tabulator stop on the frame whereby when the latter engages a tabulator stop on the carriage it is moved longitudinally to the tabulator bar to lock the type bars, for the purpose set forth.

7. In a writing machine, tabulator devices comprising the combination of a tabulator bar mounted in the carriage, tabulator stops 95 thereon, a tabulator stop mounted in the frame adapted to be moved transversely to the tabulator bar and to yield laterally parallel with the rail against the tension of a spring and having a limiting stop acting 100 when such spring is compressed, means for disengaging the carriage rack, a tabulator key and an operative connection between it and the means for disengaging the carriage rack and between it and the movable laterally yielding tabulator stop on the frame, for the purpose set forth.

8. A writing machine comprising the combination of a margin stop, a tabulator stop and a coöperating stop engaging, when in 110 normal position, the margin stop and movable to a position to engage the tabulator stop.

9. A writing machine comprising the combination of a margin stop, a tabulator stop, a 115 coöperating stop engaging, when in normal position, the margin stop and movable to a position to engage the tabulator stop and line lock devices thrown into operation whenever said coöperating stop engages either the 120 margin or tabulator stops.

10. A writing machine comprising the combination of right and left margin stops, a plurality of tabulator stops, and a coöperating stop engaging, when in normal position, 125 either of the margin stops and movable to a position to engage a tabulator stop.

11. In a writing machine, the combination of a margin stop, and tabulator devices comprising a plurality of tabulator stops, and a 130

movable part adapted in one position to engage the margin stop and in another position to engage a tabulator stop.

12. A writing machine, comprising a margin stop and tabulator stops arranged respectively in separate lines transverse to the machine, a part located intermediate the lines in which said stops are located and movable transversely thereto to coöperate with a stop in either line.

13. A writing machine, comprising a part movable longitudinally of the machine, tabulator stop which it engages in one position and a margin stop with which it engages in another position.

14. A writing machine, comprising a margin stop and tabulator stops carried by the carriage, each of said stops being adapted to arrest traverse of the carriage, and a stop on the frame engaging, when in normal position, the margin stop and adapted to be moved transversely to the axis of the platen into position to engage the tabulator stops.

15. A writing machine comprising two transversely arranged rails, one adapted to receive an adjustable margin stop and the other adjustable tabulator stops, and a movable stop arranged between the two rails and adapted to engage a stop on either of them.

16. A writing machine comprising two transversely arranged rails, one adapted to receive an adjustable margin stop and the other adjustable tabulator stops, a movable stop arranged between the two rails and adapted to engage a stop on either of them and line-lock devices thrown into operation whenever the intermediate stop engages a stop on either of said rails.

17. A writing machine comprising two transverse rails, one adapted to receive an adjustable margin stop and the other adjustable tabulator stops and a movable stop adapted in one position to engage the margin stop and in another position the tabulator stops.

18. Tabulator and margin stop devices for a writing machine, comprising an adjustable tabulator stop arranged in a line transverse to the machine, an adjustable margin stop arranged in another line transverse to the machine and a laterally yielding spring cushioned part located intermediate said lines, adapted to be moved longitudinally of the machine and acting in one position to engage the margin stop and in another position to engage the tabulator stop.

19. Tabulator and margin stop devices for a writing machine, comprising an adjustable tabulator stop arranged in a line transverse to the machine, and an adjustable margin stop arranged in another line transverse to the machine, and a laterally yielding spring-cushioned part located intermediate said lines, adapted to be moved longitudinally of the machine and acting, when in normal po-

sition, to engage the margin stop and when in a shifted position to engage the tabulator stop.

20. A writing machine comprising the combination of line-lock devices, tabulator devices and margin stop devices means whereby the line-lock devices are thrown into operation when either the tabulator or margin stop devices are in operation.

21. A writing machine comprising the combination of line-lock devices, adjustable tabulator devices, adjustable margin stop devices and means whereby the line-lock devices are thrown into operation to lock the type bars when the carriage is arrested by either the tabular devices or the line-lock devices.

22. A writing machine comprising the combination of line-lock devices, a tabulator stop arranged in a line transverse to the machine, a margin stop arranged in another transverse line, a part movable longitudinally of the machine between the lines in which the margin stop and tabulator stops are located and means whereby the linelock devices are operated when said part engages either the tabulator or margin stop.

23. A writing machine comprising the combination of a tabulator stop, a margin stop and a movable stop adapted in one position to engage the margin stop and in another position the tabulator stop, the movable stop comprising a spring cushioned part to relieve shock of impact and a part acting as a positive stop for the spring cushioned part.

24. A writing machine comprising tabulator stops carried by the carriage and a stop pivoted on the frame and movable longitudinally thereof, the pivoted stop comprising a lever movable transversely to the axis of the platen of the machine and a second spring cushioned lever pivoted thereon to rock parallel with said axis, the latter lever making contact with the tabulator stop.

25. A writing machine comprising the combination of line-lock devices, a tabulator stop arranged in a line transverse to the machine, a pivoted stop lever mounted to rock transversely to said line, a lever pivoted thereon to rock transversely of the machine, a spring for cushioning it and means whereby when the cushioned lever makes impact with the tabulator stop the line lock devices are thrown into operation to lock the type-bars.

26. A writing machine comprising the combination of a tabulator stop arranged in a line transverse to the machine, a margin stop arranged in another line transverse to the machine, a movable stop located between said transverse lines, movable longitudinally of the machine and adapted to be moved out of the path of a margin stop but not into the path of the tabulator stop, and a key and operative connections whereby the movable stop may be moved out of the path of the margin stop and into the path of the tabulator stop.

27. A writing machine comprising the com-

bination of a tabulator stop arranged in a transverse line of the machine, a margin stop arranged in another transverse line, a stop located between such lines and movable stop at right angles thereto, a rack, means for disengaging the rack, the movable stop being adapted to be moved from normal position out of the path of the margin stop, and a key and operative connections whereby the rack may be disengaged and the movable stop moved from normal position into position to engage the tabulator stop.

28. A writing machine comprising the combination of a tabulator stop arranged in a transverse line of the machine, a margin stop arranged in another transverse line, a stop located between such lines and movable stop at right angles thereto, a rack, means for disengaging the rack, the movable stop being adapted to be moved from normal position out of the path of the margin stop, a key and operative connections whereby the rack may be disengaged and the movable stop moved from normal position into position to engage the tabulator stop, and a brake for retarding jump of the carriage when the rack is disengaged.

29. A writing machine comprising the combination of a tabulator stop arranged in a transverse line of the machine, a margin stop arranged in another transverse line, a stop located between such lines and movable stop

at right angles thereto, a rack, means for disengaging the rack, the movable stop being adapted to be moved from normal position 35 out of the path of the margin stop, a key and operative connections whereby the rack may be disengaged and the movable stop moved from normal position into position to engage the tabulator stop, a brake for retarding jump 40 of the carriage when the rack is disengaged, line lock devices and means whereby they are thrown into operation whenever the movable stop engages a margin or tabulator stop.

30. In a writing machine, right and left 45 hand margin stops in a transverse plane of the machine, tabulator stops in another transverse plane, and a coöperating movable stop composed of two parts one of which is adapted, when in normal position, to contact with 50 the margin stop at the left and the other of which projects beyond the other in direction perpendicular to the axis of the platen and is in normal position, adapted to contact with the margin stop at the right and when moved 55 to tabulating position is adapted to contact with the tabulator stops.

In testimony whereof, I have hereunto subscribed my name.

EDWARD B. HESS.
